(57) **CLAIM**

The ornamental design for a connection member for the tape supporting a range of electronic parts, as shown and described.

DESCRIPTION

FIG. 1 is a perspective view of the front, bottom and left side of a connection member for the tape supporting a range of electronic parts showing my new design;

FIG. 2 is a left side view thereof;

FIG. 3 is a front view thereof;

FIG. 4 is a rear view thereof;

FIG. 5 is a top plan view thereof; and,

FIG. 6 is a bottom view thereof.

1 Claim, 2 Drawing Sheets

FIG. 1

FIG. 2

*FIG. 3**FIG. 4**FIG. 5**FIG. 6*UNITED STATES PATENT AND TRADEMARK OFFICE
CERTIFICATE OF CORRECTION

PATENT NO. : Des. 478,880 S
DATED : August 26, 2003
INVENTOR(S) : H. Sumida
